Term of patent 3½ years

(Cl. D34—5)

Fig. 1

Fig. 2

FIGURE 1 is a front elevational view of a golf club head showing my new design.

FIG. 2 is a perspective of the golf club head of FIG. 1.

The dominant features of my design reside in the portions shown in full lines, with the back of the club being conventional, said design being characterized by having horizontal lines in the striking face area and by having a pair of parallel lines on each side thereof extending transversely of and disposed adjacent to the ends of said horizontal lines with said pairs of lines converging upwardly.

I claim:

The ornamental design for a golf club head, as shown and described.
